UNITED STATES PATENT OFFICE.

JOHN J. KENNEY, OF PITTSBURGH, PENNSYLVANIA, ASSIGNOR TO BEST ELECTRIC COMPANY, OF PITTSBURGH, PENNSYLVANIA, A CORPORATION OF DELAWARE.

ATTACHMENT-PLUG.

1,338,226.

Specification of Letters Patent. Patented Apr. 27, 1920.

Application filed August 7, 1916. Serial No. 113,507.

To all whom it may concern:

Be it known that I, JOHN J. KENNEY, a resident of Pittsburgh, in the county of Allegheny and State of Pennsylvania, have invented a new and useful Improvement in Attachment-Plugs, of which the following is a specification.

This invention relates to attachment plugs for electric fixtures. The object of the invention is to provide a solid attachment plug, having an economical arrangement of parts, having the terminal conducting members carried by and attached to the main insulating body, with a threaded shell member so connected as to be easily removable to give access to the binding posts. It is designed to make the plug in one structure, which is not to be disassembled except for the first connection to conducting wires, and in which all of the parts are normally relatively immovable. Further objects are to provide efficient insulation between the conducting parts, and means for engaging the conductor wires to remove all strain on their binding posts.

These, and other objects which will appear more fully hereinafter, and which will be obvious to persons familiar with such devices, are attained by a construction, an embodiment of which is shown in the drawings.

Figure 1 is a central vertical section through the plug assembled; Fig. 2 is a central vertical section at right angles to the section of Fig. 1; Fig. 3 is a horizontal section on the line 3—3 of Fig. 1; and Fig. 4 is a diagrammatic end view of the plug.

The main body member, 1, of the plug is made of any suitable insulating material, such as glass, porcelain, rubber or composition. It is preferred to use a material such as composition or rubber, which may be molded to the desired shape at one operation. This part 1 has a central axial opening 2, adapted for the entrance of the ordinary conductor cord. This opening extends about half the length of the base member, and then opens into lateral recesses 3 and 4, which are channeled out of the sides of the base member, being shaped as shown in Figs. 1 and 3. At the bottom of the bore 2 is a smaller concentric bore 5 which extends deep enough to receive a metal insert 17,

seating therein. The bore then continues, with a smaller diameter 6 throughout the 55 base.

In the recess 3 a terminal member 7 is positioned. This is stamped from sheet metal, and has a threaded hole adapted to receive a binding post 8, and has a portion 60 adjacent to the head of this binding screw bent outwardly to form a retaining abutment 9, which has on the under side a notch 9^a, adapted to receive the conductor cord, as shown in Fig. 1. The lower end 65 of the plate 7 is bent at a right angle to the post-carrying portion, and is adapted to extend across the bottom of the base of the insulating member, having a central opening 10 therein concentric with the bore 70 6, and having transverse wings 11 extending diametrically from this central opening, as shown in Fig. 4. The ends of these wings have holes 12 adapted to receive screws 13, as below described.

The recess 4 houses another terminal conducting member 14, stamped from sheet metal, having a threaded hole therein adapted to receive binding post 15, and having an adjacent portion bent outwardly 80 to form an abutment 16 to coöperate with said binding post, with a notch 16^a on the under side. This plate is extended, in the form of a metal strip, past the end of the insulating base 1, and then bent over at 85 right angles across the center of the base, and has a hole therein alined with the bore 6.

The terminal member 7 is first placed in position, an insulating ring 18 is fitted into 90 the opening 10, and another annular insulating member 19, having a central opening alined with bore 6. The terminal member 14 is then placed in position in the recess 4, with its transverse portion across the insulating member 19, and with its opening alined with the bore through the insulating base and member 19. A screw 20 is then passed through members 14, 19, 18 and the base 1, and is threaded into the insert 17, 100 above described. This binds all of the parts mentioned rigidly in the relative positions shown in Fig. 1.

Conductor wires are led in through the opening 2, passing under the abutments and 105 engaging the notches therein, and then made

fast to the binding posts, as will be obvious. This entirely relieves the strain of the wires on the binding posts. The threaded metal shell 21, in the form of a cup with an opening 22 in its bottom, and containing an interior insulating sleeve, or shell 22^a, is then slipped over the base. This threaded shell bears against the conducting member 7, and the screws 13 pass through openings 10 in the shell and are threaded into the member 7, as above described. The opening 22 is cut away, as shown in Fig. 4, to give ample clearance for passage therethrough of the conducting terminal 14. By this arrangement the terminal 7 is directly connected to the outer contact shell 21, and the conductor terminal 14 is insulated therefrom and in position to contact with the central terminal of the socket in which the plug is 20 used.

It will be observed that access to the binding posts for insertion or removal of conducting wires is readily obtained by withdrawing the screws 13, and slipping off the shell 21. This leaves the binding posts completely exposed, and any changes may be made, without further disassembling the plug. Furthermore, the notched abutment about which the conductor wires are led 25 before being engaged by the binding posts, gives a complete doubling upon itself to the wires. This takes practically all strain off the binding posts.

An annular rib 23 is provided around the upper end of the base, and is preferably 35 roughened, or corrugated, to form a suitable hand-hold.

I claim:—

1. A solid attachment plug, comprising an integral insulating base having a central 40 bore for receiving conductor wires and lateral longitudinal recesses for housing conductor terminals, terminals in said recesses having their lower ends bent over across the end of the base and one of them forming the central contact of the plug, a separating insulating member, a threaded outer contact shell attached to one conductor terminal, and a central terminal contact screw 45 engaging the other conductor terminal and 50 binding all of the parts to the base.

2. In combination with an attachment plug comprising an insulating base having recesses for housing conductor terminals and an outer contact shell, conductor terminals 55 carrying binding screws and having lateral wings turned over to form abutments having notches therein adapted to receive conductor cords passed around the abutments to the binding screw.

In testimony whereof, I have hereunto set my hand.

JOHN J. KENNEY.
